ENGRAVING MACHINE

Werner J. Larson, West Hartford, Conn.

Application February 26, 1946, Serial No. 650,158

18 Claims. (Cl. 33—25)

1

This invention relates particularly to an engraving machine of the pantograph type, particularly adapted for the marking of tools, machine parts and the like. In using the machine a master is provided carrying the words, numbers and symbols to be engraved on the work piece, and the master is traced by a movable stylus. By means of pantograph linkage the pattern of the master is engraved on the work piece on a reduced scale by means of a suitable engraving tool.

The principal object of the invention is to provide for a machine of the class described, improved means for adjusting the pantograph linkage to vary the ratio of size reduction from the master to the work piece.

A specific object of the invention is to provide means for adjusting the effective length of one link in association with means for correspondingly adjusting the effective length of another link.

Another specific object of the invention is to provide graduations in association with one link for indicating the adjustments in effective length that are necessary for various ratios of reduction, together with means dependent on the effective length of the first link for determining the extent of corresponding adjustment of another link.

Still other specific objects of the invention will be apparent from the following specification and claims.

In the drawings I have shown in detail a preferred embodiment of the invention, but it will be understood that various changes may be made from the construction shown, and that the drawings are not to be construed as defining or limiting the scope of the invention, the claims forming a part of this specification being relied upon for that purpose.

Of the drawings,

Fig. 1 is a perspective view of a machine embodying the invention.

Fig. 2 is a plan view of the portions of the machine to which the invention more particularly relates.

Fig. 3 is a horizontal sectional view of the portion of the machine shown in Fig. 2, this view being taken along the line 3—3 of Fig. 4.

Fig. 4 is a front view of the parts shown in Figs. 2 and 3.

Fig. 5 is a vertical sectional view taken along the line 5—5 of Fig. 4.

Fig. 6 is a fragmentary vertical sectional view taken along the line 6—6 of Fig. 5.

2

Fig. 7 is an enlarged fragmentary vertical sectional view taken along the line 7—7 of Fig. 5.

Fig. 8 is an enlarged fragmentary vertical sectional view taken along the line 8—8 of Fig. 5.

Fig. 9 is a view similar to Fig. 8 but showing the parts in different relative positions.

Figs. 10 and 11 are views similar to Fig. 2 but showing the parts in different relative positions.

Fig. 12 is a diagrammatic view showing the relative movements of the linkage during engraving, it being assumed that the parts are adjusted to the relative positions shown in Fig. 10.

The main frame of the machine may be of any usual or preferred form and a main frame of conventional construction is illustrated. The main frame comprises two end members 10 and 12 which are connected by horizontal rods 14, 14. Supported on the rods 14, 14 and adjustable therealong is a support 16 having a platform 18 which carries the pattern or master which is to be traced in the engraving operation. As shown, the platform 18 is provided with grooved members 20, 20 adapted to position and hold removable elements 22, 22 having letters or numbers formed as grooves therein. These letter members 22, 22 constitute the master and they are adapted to be traced by a stylus to be described.

The rods 14, 14 also carry a support 24 which is adjustable therealong and which is adapted to support a work piece such as 26 to be engraved. The support 24 carries suitable means for holding the work piece, and this may be a magnetic chuck, as indicated at 28, together with a spacing block 29. In the operation of the machine a stylus 30 is manually moved to follow or trace the master 22, 22, and by means of pantograph linkage, to which the invention more particularly relates, the stylus causes an engraving tool 32 to reproduce the pattern of the master on the work piece 26, such reproduction being on a reduced scale.

For supporting the pantograph linkage the end member 12 of the main frame has an upstanding portion 34 carrying a bracket 36 to which the pantograph linkage is pivoted. The pantograph linkage comprises two main links connected with each other at a movable main pivotal axis and two auxiliary links connected with each other at a movable auxiliary pivotal axis, the said auxiliary links being connected with the main links at secondary pivotal axes. In accordance with the invention, the main links are so formed that their effective lengths can be changed and each 55 of them preferably comprises a main link member

and a link extension, and said member and said extension being relatively movable longitudinally.

Referring particularly to Figs. 2 and 3, one main link member is shown at 38 and the corresponding link extension is shown at 40. These members have tongue and groove engagement and the member 38 can be moved longitudinally with respect to the extension 40. The members can be locked in their adjusted positions by means of a nut 42 and screw 44. The extension 40 is pivotally connected with the bracket 36 for movement about a vertical fixed or stationary axis at 46. The extension 40 is provided with horizontally projecting ears 48, 48 which are spaced apart so that the link member 38 can move between them.

The other main link member is shown at 50, this being pivotally connected with the member 38 for relatively pivotal movement about a vertical axis at 52, which axis will be designated as the "main" axis. The axis 52 is so positioned that movement of the member 38 with respect to the extension 40 causes the said axis to move in a plane extending through the stationary axis 46. Associated with the link member 50 is an extension 54 which is longitudinally adjustable relatively thereto, the said link member and extension having tongue and groove engagement. The parts can be locked in their adjusted positions by means of a nut 56 engaging a screw 58. The extension 54 carries the said stylus 30, the stylus being vertically movable with respect to the extension so as to enable it to be engaged with or removed from the master 22, 22. The axis of the stylus 30 is so positioned on the extension 54 that when the said extension is moved longitudinally with respect to the link member 50 the said axis moves in a plane through the movable main axis 52.

The auxiliary pantograph links are shown at 60 and 62, these being pivotally connected with each other at a movable pivotal axis 64, which axis will be designated as the "auxiliary" axis. The auxiliary links 60 and 62 are connected respectively with the main link members 38 and 50 at axes 66 and 68, which axes will be designated as the "secondary" axes. The axes 52, 68, 66 and 64 are so spaced as to be positioned at the corners of a rectangle when the links are in the predetermined relative positions shown in Figs. 2 and 3. While the invention is not necessarily so limited, the said axes are preferably so spaced that they are at the corners of a square when in the said predetermined positions. It will be observed that the axis 66 is in the same vertical plane as the axes 52 and 46 and that the axis 68 is in the same vertical plane as the axes 52 and 30.

The engraving tool 32 is carried by the auxiliary links 60 and 62 at the said movable auxiliary pivotal axis 64. This engraving tool may be of any usual or suitable type, but without intending to in any way limit the invention, I have illustrated an engraving tool adapted for electric etching. This comprises a pointed rod 70 which extends through an insulating bushing 72 and which is connected at its upper end with an electric conductor 74. The bushing 72 is vertically adjustable and is held in its adjusted position by a set screw 75. A spring 76 biases the rod 70 to an elevated position and during engraving the rod is pressed downward manually so as to engage the work piece 26. It will be understood that the conductor 74 is connected with a suitable source of electrical energy, which source is grounded to the main frame of the machine. When the rod

is in engagement with the work piece the surface of the said work piece at the point of the rod is heated sufficiently to make a mark thereon as the rod is moved. The manner of operation of the electric engraving tool is well understood and further description is unnecessary.

In order to change the ratio of reduction from the master 22, 22 to the work piece 26, the effective lengths of two of the pantograph links must be changed and the length changes must be properly correlated. In accordance with the invention, one of the links has means relatively movable in accordance with the changes in length thereof and serving as a guide for determining the amounts of necessary changes in length of the other of the said links. The said movable means on one link preferably has a contour line thereon, and the other link has a setting member which can be brought into register with the said contour line. When the setting member is in register with the contour line, the said other link has been changed in length in accordance with the change in length of the first mentioned link.

In the preferred construction as shown, the said ratio of reduction is determined by the adjustment of the extension 54 with respect to the member 50 and by the adjustment of the member 38 with respect to the extension 40. These adjustments are made with the several links in predetermined "primary" positions. While the invention is not necessarily so limited, the said predetermined primary positions are preferably the said predetermined positions which are shown in Figs. 2, 3, 10 and 11. In order that the extension 54 may be readily adjusted for any desired reduction ratio, the said extension 54 is provided with a control member or plate 78 having graduations marked thereon, as indicated at 80. The link member 50 carries a pointer 82 which overlies the plate 78 to cooperate with the graduations 80 thereon. The machine, as illustrated, is particularly intended for use with letter elements 22, 22 having letters which are $\frac{1}{2}$ inch in height. The graduations 80 are such as to indicate the actual height of the letters or numbers to be reproduced on the work piece 26. For instance, as shown in Fig. 2, the adjustment is such as to produce letters on the work piece having a height of .090 inch, but inasmuch as the height of the letters on the master is $\frac{1}{2}$ inch, the ratio of reproduction is twice the amount indicated by the marking, that is .180.

The aforesaid ratio of reduction is the same as the ratio between the distance a from the main movable axis 52 to the adjacent secondary axis 68 and the distance b from the said main axis 52 to the axis of the stylus 30.

It will be seen that the effective length of one main link (comprising the members 50 and 54) is adjusted to effect the desired ratio of reduction in the manner that has been described. It is necessary to also similarly adjust the effective length of the other main link (comprising the members 38 and 40) and this is done by adjusting the link member 38 longitudinally of the link extension 40. In order that the last said adjustment may be made conveniently, the said extension 40 is provided with a setting member which is brought into direct juxtaposition with the control member or plate 78 after the extension 54 with the said plate 78 thereon has been properly adjusted to the desired ratio. As shown, the plate 78 is provided with a contour line 84 thereon and the extension 40 is provided with a setting member 86 which is adapted to register vertically

with the said contour line 84. Preferably, but not necessarily, the plate 78 constitutes an abutment member and its edge is shaped to conform to the contour line 84 and the setting member 86 is in the form of a stop adapted to abut directly against the contoured edge of the plate. After the member 54 with the plate 78 thereon has been adjusted to the desired reduction ratio, it is merely necessary to then adjust the link member 38 on the extension 40 so that the setting member or stop 86 engages the contour 84. The shape of the contour is such that, when the stop is in engagement therewith, the effective length of the main link comprising the members 38 and 40 is correct for the desired ratio of reduction. Thus the contour line or edge 84 on the link comprising the members 50 and 54 serves as a guide for changing the effective length of the link comprising the members 38 and 40. The said correct ratio is the ratio between the distance c from the fixed or stationary axis 46 to the adjacent auxiliary axis 66 and the distance d from the said fixed or stationary axis 46 to the main movable axis 52. In other words, the construction which has been described makes it possible for the user of the machine to conveniently and quickly make the necessary adjustments so that the ratio of c to d is the same as the ratio of a to b , this ratio being the reduction ratio of the machine.

Preferably, the stop 86 is so mounted that it can be maintained out of its contacting position at all times except when actually needed for determining the proper adjustment. As shown more clearly in Figs. 6 to 9, the extension 40 carries a horizontal rod 88 on which is a rotatable bushing 90 held in place by a screw 92 and a washer 94. The stop 86 is formed as an integral extension on the bushing 90. The bushing 90 is provided with an arcuate notch 96 as shown in Fig. 7, and the extension 40 carries a pin 98 which projects into the notch to limit the extent of rotation of the bushing. The bushing carries a handle 100 by means of which it may be turned. Fig. 8 shows the stop 86 in its vertical position wherein it is adapted to engage with the contour 84 at the edge of the plate 78. By means of the handle 100, the parts can be adjusted to the relative positions shown in Fig. 9 wherein the stop 86 is above the plate 78 and free from engagement therewith.

It has already been stated that the adjustments of the effective lengths of the main links are made with the several links in their primary positions, which are preferably the positions shown in Figs. 2, 4, 10 and 11. A suitable means is preferably provided for releasably holding the links in their said primary positions, and as shown, this means comprises a resilient member 102 carried by one of the links as for instance by the auxiliary link 60. The member 102 extends across the space between the links and is adapted to engage the opposite link, as for instance the main link member 50. The pivot members for the pivotal connections at 52 and 68 are provided with heads 104 and 106 and the member 102 is of such size that, when manually depressed, it can fit between the two heads 104 and 106 to hold all of the links in their primary positions. The resiliency of the member 102 is such that it normally lies above the level of the heads 104 and 106, as shown in Fig. 5. Thus, the links are normally free to move without any restriction by the said member 102 but can be locked in their primary positions when the member 102 is manually depressed.

Figs. 10 and 11 are similar to Fig. 2, except

that the parts are in different positions of adjustment. In Fig. 10 the adjustment is such as to produce letters .125" in height, this representing a reduction ratio of .25. The distance a between the axes 52 and 68 remains the same, but the distance b' which corresponds to b in Fig. 2 is reduced so that the ratio of a to b' is .25. By bringing the stop 86 into engagement with the contour 84, the distances c' and d' which correspond to c and d in Fig. 2 have been changed so that the ratio of c' to d' is .25.

In Fig. 11 the adjustment is such as to produce letters .250" in height, this representing a reduction ratio of .5. The distance a remains the same but the distance b'' which corresponds to b and b' in Figs. 2 and 10 is reduced so that the ratio of a to b'' is .5. By bringing the stop 86 into engagement with the contour 84, the distances c'' and d'' which correspond to the distances c , c' and d , d' in Figs. 2 and 10 have been changed so that the ratio of c'' to d'' is .5.

Fig. 12 is a diagrammatic view showing the relative movements of the parts, the adjustment being the same as in Fig. 10. This view illustrates the positions of the links and of the engraving tool for various positions of the stylus in tracing a word on the pattern.

What I claim is:

1. In an engraving machine comprising pantograph links which include two pivotally connected main links, the combination of means for changing the effective length of one main link, means for changing the effective length of the other main link, a setting member on one of the said main links relatively movable in accordance with changes in the effective length of the said link, and a control member on the other of the said main links relatively movable in accordance with changes in the effective length of the said link, the said setting member on the first said link being movable into direct juxtaposition with the control member on the second said main link and being so movable to different extents according to different relative positions of the control member and the said control member by reason of the said different extents of movement of the setting member serving to determine the correct change in the effective length of the first said main link corresponding to each change in the effective length of the second said main link.

2. In an engraving machine comprising pantograph links which include two pivotally connected main links, the combination of means for changing the effective length of one main link, means for changing the effective length of the other main link, a setting member on one of the said main links relatively movable in accordance with changes in the effective length of the said link, and a control member on the other of the said main links relatively movable in accordance with changes in the effective length of the said link, the said control member having a contour line thereon which is so positioned that the setting member is movable into register therewith and which is so shaped that the setting member upon movement into register therewith is moved to different extents according to different relative positions of the control member and of the contour line thereon and the said control member by reason of the said different extents of movement of the setting member serving to determine the correct change in the effective length of the first said main link corresponding to each change in the effective length of the second said main link.

3. In an engraving machine comprising pantograph links which include two pivotally connected main links, the combination of means for changing the effective length of one main link, means for changing the effective length of the other main link, a setting member on one of the said main links relatively movable in accordance with changes in the effective length of the said link, and an abutment member on the other of the said main links relatively movable in accordance with changes in the effective length of the said link, the said abutment member having a contour edge which is so positioned that the setting member is movable into direct abutment therewith and which is so shaped that the setting member upon being moved into abutment therewith is moved to different extents according to different relative positions of the control member and of the contour edge thereof and the said abutment member by reason of the said different extents of movement of the setting member serving to determine the correct change in the effective length of the first said main link corresponding to each change in the effective length of the second said main link.

4. In an engraving machine, the combination of two main pantograph links connected at a movable main pivotal axis and two auxiliary pantograph links connected at a movable auxiliary pivotal axis, the said main and auxiliary links being connected with each other at movable secondary pivotal axes so that when the links are in predetermined positions their several pivotal axes are at the corners of a rectangle, means for connecting one main link for movement about a fixed pivotal axis in the same plane as the main axis and the adjacent secondary axis, a stylus carried by the other main link with its axis in the same plane as the main axis and the adjacent secondary axis, the said stylus being adapted to follow a master held in a stationary position, an engraving tool carried by the auxiliary links, means for changing the effective length of the second main link to change the distance between the stylus and the movable main axis, means for changing the effective length of the first main link to change the distance between the movable main axis and the fixed axis, a control member on one of the said main links relatively movable in accordance with changes in the effective length of the said link, and a setting member on the other of the said main links which is relatively movable in accordance with changes in the effective length of the said link, the said setting member being movable into direct juxtaposition with the control member and the said setting member upon being so moved with the main links located in predetermined primary positions serving to determine the correct change in the effective length of the setting member carrying link to correspond to each change in the effective length of the control member carrying link.

5. An engraving machine as set forth in claim 1, wherein the links are in the said predetermined primary positions when the several pivotal axes are at the corners of a rectangle.

6. In an engraving machine, the combination of two main pantograph links connected at a movable main pivotal axis and two auxiliary pantograph links connected at a movable auxiliary pivotal axis, the said main and auxiliary links being connected with each other at movable secondary pivotal axes so that when the links are in predetermined positions their several pivotal axes are at the corners of a

rectangle, means for connecting one main link for movement about a fixed pivotal axis in the same plane as the main axis and the adjacent secondary axis, a stylus carried by the other main link with its axis in the same plane as the main axis and the adjacent secondary axis, the said stylus being adapted to follow a master held in a stationary position, an engraving tool carried by the auxiliary links, means for changing the effective length of the second main link to change the distance between the stylus and the movable main axis, means for changing the effective length of the first main link to change the distance between the movable main axis and the fixed axis, an abutment member on the main link carrying the stylus which abutment member is relatively movable in accordance with changes in the effective length of the last said link and which abutment member has a contour edge, and a setting member on the other main link which member is relatively movable in accordance with changes in the effective length of the said link, the said setting member being movable into direct abutment with the contour edge of the abutment member on the said stylus carrying main link and the said setting member upon being so moved with the main links located in predetermined primary positions serving to determine the correct change in the effective length of the setting member carrying link to correspond to each change in the effective length of the abutment member carrying link.

7. In an engraving machine, the combination of two main pantograph links connected at a movable main pivotal axis and two auxiliary pantograph links connected at a movable auxiliary pivotal axis, the said main and auxiliary links being connected with each other at movable secondary pivotal axes so that when the links are in predetermined positions their several pivotal axes are at the corners of a rectangle, means for connecting one main link for movement about a fixed pivotal axis in the same plane as the main axis and the adjacent secondary axis, a stylus carried by the other main link with its axis in the same plane as the main axis and the adjacent secondary axis, the said stylus being adapted to follow a master held in a stationary position, an engraving tool carried by the auxiliary links, means for changing the effective length of the second main link to change the distance between the stylus and the movable main axis, means for changing the effective length of the first main link to change the distance between the movable main axis and the fixed axis, control means carried by one main link and movable in accordance with the change in length thereof for determining the amount of change of length of the other main link which means is operable with the links in predetermined primary positions, and means for releasably holding the links in their said primary positions while the lengths of the main links are being changed.

8. The combination in an engraving machine, of two main pantograph link members connected at a movable main pivotal axis and two auxiliary pantograph links connected at a movable auxiliary pivotal axis, the said main link members and auxiliary links being connected with each other at movable secondary pivotal axes so that when the link members and links are in predetermined positions their several pivotal axes are at the corners of a rectangle, a link extension carrying one main link member which is longitudinally movable relatively thereto, means for

mounting the extension for movement about a fixed pivotal axis in the same plane as the main axis and the adjacent secondary axis, a link extension connected with the other main link member and longitudinally movable relatively thereto, a stylus carried by the last said link extension with its axis in the same plane as the main axis and the adjacent secondary axis, the said stylus being adapted to follow a master held in a stationary position, an engraving tool carried by the two auxiliary links at the auxiliary pivotal axis and adapted to engrave a work piece held in a stationary position, a setting member carried by the first said link extension, and a control member carried by and movable with the second said link extension, the said control member being positioned for cooperation with the said setting member and having a contour line thereon so shaped that when the main link members and auxiliary links are in predetermined primary positions and when the setting member is in register with the said line the ratio of the distances between the fixed axis and the secondary axis adjacent the first link member and between the fixed axis and the main axis bears a predetermined relation to the ratio of the distances between the main axis and the secondary axis adjacent the second link member and between the main axis and the axis of the stylus.

9. The combination in an engraving machine, of two main pantograph link members connected at a movable main pivotal axis and two auxiliary pantograph links connected at a movable auxiliary pivotal axis, the said main link members and auxiliary links being connected with each other at movable secondary pivotal axes so that when the link members and links are in predetermined positions their several pivotal axes are at the corners of a rectangle, a link extension carrying one main link member which is longitudinally movable relatively thereto, means for mounting the said extension for movement about a fixed pivotal axis in the same plane as the main axis and the adjacent secondary axis, a link extension connected with the other main link member and longitudinally movable relatively thereto, a stylus carried by the last said link extension with its axis in the same plane as the main axis and the adjacent secondary axis, the said stylus being adapted to follow a master held in a stationary position, an engraving tool carried by the two auxiliary links at the auxiliary pivotal axis and adapted to engrave a work piece held in a stationary position, a setting member carried by the first said link extension, and a control member carried by and movable with the second said link extension, the said control member being positioned for cooperation with the said setting member and having a contour line thereon so shaped that when the main link members and auxiliary links are in predetermined primary positions and when the setting member is in register with the said line the ratio of the distances between the fixed axis and the secondary axis adjacent the first link member and between the fixed axis and the main axis is the same as the ratio of the distances between the main axis and the secondary axis adjacent the second link member and between the main axis and the axis of the stylus.

10. The combination in an engraving machine, of two main pantograph link members connected at a movable main pivotal axis and two auxiliary pantograph links connected at a movable auxiliary pivotal axis, the said main link members

and auxiliary links being connected with each other at movable secondary pivotal axes so that when the link members and links are in predetermined positions their several pivotal axes are at the corners of a rectangle, a link extension carrying one main link member which is longitudinally movable relatively thereto, means for mounting the said extension for movement about a fixed pivotal axis in the same plane as the main axis and the adjacent secondary axis, a link extension connected with the other main link member and longitudinally movable relatively thereto, a stylus carried by the last said link extension with its axis in the same plane as the main axis and the adjacent secondary axis, the said stylus being adapted to follow a master held in a stationary position, an engraving tool carried by the two auxiliary links at the auxiliary pivotal axis and adapted to engrave a work piece held in a stationary position, a setting member carried by the first said link extension, a control member carried by and movable with the second said link extension, the said control member being positioned for cooperation with the said setting member and having a contour line thereon so shaped that when the main link members and auxiliary links are in predetermined primary positions and when the setting member is in register with the said line the ratio of the distances between the fixed axis and the secondary axis adjacent the first link member and between the fixed axis and the main axis is the same as the ratio of the distances between the main axis and the secondary axis adjacent the second link member and between the main axis and the axis of the stylus, and means for releasably holding the links in their said primary positions while relative longitudinal movement is being effected between the main link members and their extensions.

11. The combination in an engraving machine, of two main pantograph links each comprising a link member and an extension therefor which are relatively movable longitudinally, the said link members being connected at a movable main pivotal axis, two auxiliary pantograph links connected at a movable auxiliary pivotal axis, the said link members and auxiliary links being connected with each other at movable secondary pivotal axes so that when the link members and links are in predetermined positions their several pivotal axes are at the corners of a rectangle, means for mounting the extension on one main link for movement about a fixed pivotal axis in the same plane as the main axis and the adjacent secondary axis, a stylus carried by the link extension of the other main link with its axis in the same plane as the main axis and the adjacent secondary axis, the said stylus being adapted to follow a master held in a stationary position, an engraving tool carried by the two auxiliary links at the auxiliary pivotal axis and adapted to engrave a work piece held in a stationary position, a setting member carried by the first said link extension, a control member carried by and movable with the second said link extension, the said control member being positioned for cooperation with the said setting member and having a contour line thereon so shaped that when the main link members and auxiliary links are in predetermined primary positions and when the setting member is in register with the said line the ratio of the distances between the fixed axis and the secondary axis adjacent the first link member and between the fixed axis and the main axis is the same as the ratio of the distances between the main axis and the secondary axis adjacent the second link member and between the main axis and the axis of the stylus.

the main axis is the same as the ratio of the distances between the main axis and the secondary axis adjacent the second link member and between the main axis and the axis of the stylus, and means carried by one link and adapted to engage the link opposite thereto for releasably holding the links in their said primary positions while relative longitudinal movement is being effected between the main link members and their extensions.

12. The combination in an engraving machine, of two main pantograph link members connected at a movable main pivotal axis and two auxiliary pantograph links connected at a movable auxiliary pivotal axis, the said main link members and auxiliary links being connected with each other at movable secondary pivotal axes so that when the link members and links are in predetermined positions their several pivotal axes are at the corners of a rectangle, a link extension carrying one main link member which is longitudinally movable relatively thereto, means for mounting the said extension for movement about a fixed pivotal axis in the same plane as the main axis and the adjacent secondary axis, a link extension connected with the other main link member and longitudinally movable relatively thereto, a stylus carried by the last said link extension with its axis in the same plane as the main axis and the adjacent secondary axis, the said stylus being adapted to follow a master held in a stationary position, an engraving tool carried by the two auxiliary links at the auxiliary pivotal axis and adapted to engrave a work piece held in a stationary position, a setting member carried by the first said link extension, a control member carried by and movable with the second said link extension, the said control member being positioned for cooperation with the said setting member and having a contour line thereon so shaped that when the main link members and auxiliary links are in predetermined primary positions and when the setting member is in register with the said line the ratio of the distances between the fixed axis and the secondary axis adjacent the first link member and between the fixed axis and the main axis is the same as the ratio of the distances between the main axis and the secondary axis adjacent the second link member and between the main axis and the axis of the stylus, graduations on the control member showing various ratios, and a pointer on the second link member cooperating with the said graduations to show the aforesaid ratios of distances for various positions of the control member.

13. The combination in an engraving machine, of two main pantograph link members connected at a movable main pivotal axis and two auxiliary pantograph links connected at a movable auxiliary pivotal axis, the said main link members and auxiliary links being connected with each other at movable secondary pivotal axes so that when the link members and links are in predetermined positions their several pivotal axes are at the corners of a rectangle, a link extension carrying one main link member which is longitudinally movable relatively thereto, means for mounting the said extension for movement about a fixed pivotal axis in the same plane as the main axis and the adjacent secondary axis, a link extension connected with the other main link member and longitudinally movable relatively thereto, a stylus carried by the last said link extension with its axis in the same plane as the main axis and the adjacent secondary axis, the

said stylus being adapted to follow a master held in a stationary position, an engraving tool carried by the two auxiliary links at the auxiliary pivotal axis and adapted to engrave a work piece held in a stationary position, a setting member carried by the first said link extension, a control member carried by and movable with the second said link extension, the said control member being positioned for cooperation with the said setting member and having a contour line thereon so shaped that when the main link members and auxiliary links are in predetermined primary positions and when the setting member is in register with the said line the ratio of the distances between the fixed axis and the secondary axis adjacent the first link member and between the fixed axis and the main axis is the same as the ratio of the distances between the main axis and the secondary axis adjacent the second link member and between the main axis and the axis of the stylus, graduations on the control member showing various ratios of size reduction between the stylus and the engraving tool which ratios are the same as the ratios aforesaid, and a pointer on the second link member cooperating with the said graduations to show the ratio of size reduction for each setting.

14. The combination in an engraving machine, of two main pantograph link members connected at a movable main pivotal axis and two auxiliary pantograph links connected at a movable auxiliary pivotal axis, the said main link members and auxiliary links being connected with each other at movable secondary pivotal axes so that when the link members and links are in predetermined positions their several pivotal axes are at the corners of a rectangle, a link extension carrying one main link member which is longitudinally movable relatively to the said extension, means for mounting the said extension for movement about a fixed pivotal axis in the same plane as the main axis and the adjacent secondary axis, a link extension connected with the other main link member and longitudinally movable relatively thereto, a stylus carried by the last said link extension with its axis in the same plane as the main axis and the adjacent secondary axis, the said stylus being adapted to follow a master held in a stationary position, an engraving tool carried by the two auxiliary links at the auxiliary pivotal axis and adapted to engrave a work piece held in a stationary position, a stop carried by the first said link extension, and an abutment member carried by and movable with the second said link extension, the said abutment member being positioned to be engaged by the said stop and having its edge so shaped that when the main link members and the auxiliary links are in predetermined primary positions and when the stop is engaged with the said edge the ratio of the distances between the fixed axis and the secondary axis adjacent the first link member and between the fixed axis and the main axis is the same as the ratio of the distances between the main axis and the secondary axis adjacent the second link member and between the main axis and the axis of the stylus.

15. The combination in an engraving machine, of two main pantograph link members connected at a movable main pivotal axis and two auxiliary pantograph links connected at a movable auxiliary pivotal axis, the said main link members and auxiliary links being connected with each other at movable secondary pivotal axes so that when the link members and links are in predetermined

positions their several pivotal axes are at the corners of a rectangle, a link extension carrying one main link member which is longitudinally movable relatively to the said extension, means for mounting the said extension for movement about a fixed pivotal axis in the same plane as the main axis and the adjacent secondary axis, a link extension connected with the other main link member and longitudinally movable relatively thereto, a stylus carried by the said last link extension with its axis in the same plane as the main axis and the adjacent secondary axis, the said stylus being adapted to follow a master held in a stationary position, an engraving tool carried by the two auxiliary links at the auxiliary pivotal axis and adapted to engrave a work piece held in a stationary position, a stop carried by the first said link extension, an abutment member carried by and movable with the second said link extension, the said abutment member being positioned to be engaged by the said stop and having its edge so shaped that when the main link members and the auxiliary links are in predetermined primary positions and when the stop is engaged with the said edge the ratio of the distances between the fixed axis and the secondary axis adjacent the first link member and between the fixed axis and the main axis is the same as the ratio of the distances between the main axis and the secondary axis adjacent the second link member and between the main axis and the axis of the stylus, graduations on the abutment member showing various ratios, and a pointer on the second link member cooperating with the said graduations to show the aforesaid ratios of distances for various positions of the abutment member.

16. The combination in an engraving machine, of two main pantograph link members connected at a movable main pivotal axis and two auxiliary pantograph links connected at a movable auxiliary pivotal axis, the said main link members and auxiliary links being connected with each other at movable secondary pivotal axes so that when the link members and links are in predetermined positions their several pivotal axes are at the corners of a rectangle, a link extension carrying one main link member which is longitudinally movable relatively to the said extension, means for mounting the said extension for movement about a fixed pivotal axis in the same plane as the main axis and the adjacent secondary axis, a link extension connected with the other main link member and longitudinally movable relatively thereto, a stylus carried by the last said link extension with its axis in the same plane as the main axis and the adjacent secondary axis, the said stylus being adapted to follow a master held in a stationary position, an engraving tool carried by the two auxiliary links at the auxiliary pivotal axis and adapted to engrave a work piece held in a stationary position, a stop carried by the first said link extension, an abutment member carried by and movable with the second said link extension, the said abutment member being positioned to be engaged by the said stop and having its edge so shaped that when the main link members and the auxiliary links are in predetermined primary positions and when the stop is engaged with the said edge the ratio of the distances between the fixed axis and the secondary axis adjacent the first link member and between the fixed axis and the main axis is the same as the ratio of the distances between the main axis and the secondary axis adjacent the second link member and between the main axis and the axis of the stylus,

and means for moving the stop out of cooperative relationship with the abutment member to avoid contact therewith during engraving.

17. An engraving machine comprising in combination, a main frame, a main link extension pivoted to the main frame for movement about a fixed axis, a main link member carried by the said extension and longitudinally adjustable with respect thereto, a second main link member pivotally connected with the first main link member for relative movement about a main axis, the said main axis being positioned to move relatively to the said link extension in a plane passing through the fixed axis, a second main link extension carried by the second main link member and longitudinally movable with respect thereto, a stylus carried by the second main link extension and positioned to move relatively to the second main link member in a plane passing through the main axis, the said stylus being adapted to follow a master stationarily held on the main frame, two auxiliary links pivotally connected with each other for relative movement about an auxiliary axis, the said auxiliary links being pivotally connected respectively with the said main link members for relative movement about secondary axes with one such axis in the plane extending through the fixed axis and the main axis and with the other such axis in the plane extending through the main axis and the axis of the stylus and the distances between the several movable axes being such that they are at the corners of a rectangle when the main link members and auxiliary links are in predetermined positions, an engraving tool carried by the auxiliary links at the said auxiliary axis and adapted to engrave a work piece stationarily held on the main frame, a setting member carried by the first said link extension, and a control member carried by and movable with the second said link extension, the said control member being positioned for cooperation with the said setting member and having a contour line thereon so shaped that when the main link members and auxiliary links are in predetermined primary positions and when the setting member is in register with the said line the ratio of the distances between the fixed axis and the secondary axis adjacent the first link member and between the fixed axis and the main axis is the same as the ratio of the distances between the main axis and the secondary axis adjacent the second link member and between the main axis and the axis of the stylus.

18. An engraving machine comprising in combination, a main frame, a main link extension pivoted to the main frame for movement about a fixed axis, a main link member carried by the said extension and longitudinally adjustable with respect thereto, a second main link member pivotally connected with the first main link member for relative movement about a main axis, the said main axis being positioned to move relatively to the said link extension in a plane passing through the fixed axis, a second main link extension carried by the second main link member and longitudinally movable with respect thereto, a stylus carried by the second main link extension and positioned to move relatively to the second main link member in a plane passing through the main axis, the said stylus being adapted to follow a master stationarily held on the main frame, two auxiliary links pivotally connected with each other for relative movement about an auxiliary axis, the said auxiliary links being pivotally con-

15

nnected respectively with the said main link members for relative movement about secondary axes with one such axis in the plane extending through the fixed axis and the main axis and with the other such axis in the plane extending through the main axis and the axis of the stylus and the distances between the several movable axes being such that they are at the corners of a rectangle when the main link members and auxiliary links are in predetermined positions, an engraving tool carried by the auxiliary links at the said auxiliary axis and adapted to engrave a work piece stationarily held on the main frame, a stop carried by the first said link extension, an abutment member carried by and movable with the second said link extension, the said abutment member being positioned to be engaged by the said stop and having its edge so shaped that when the main link members and the auxiliary links are in predetermined primary positions and when the stop is engaged with the said edge the ratio of the distances between the fixed axis and the sec-
